UNITED STATES PATENT OFFICE.

DAVID H. MOORE, OF SEATTLE, WASHINGTON.

DESIGN FOR A VASE.

40,584.

Specification for Design. Patented Mar. 22, 1910.

Application filed January 11, 1910. Serial No. 537,563. Term of patent 14 years.

To all whom it may concern:

Be it known that I, DAVID H. MOORE, a citizen of the United States, residing at Seattle, in the county of King and State of Washington, have invented a new, original, and ornamental Design for a Vase, of which the following is a specification, reference being had to the accompanying drawings, forming a part thereof.

The figure is a perspective view of a vase, showing my design.

I claim:

The ornamental design for a vase, as shown.

DAVID H. MOORE.
